UNITED STATES PATENT OFFICE.

HENRY BERGH, OF NEW YORK, N. Y.

TOY MOTOR-BOAT.

1,116,215.

Specification of Letters Patent. Patented Nov. 3, 1914.

Application filed June 11, 1914. Serial No. 844,474.

To all whom it may concern:

Be it known that I, HENRY BERGH, a citizen of the United States, and a resident of the city of New York, borough of Manhattan, in the county and State of New York, have invented a new and Improved Toy Motor-Boat, of which the following is a full, clear, and exact description.

Among the principal objects which the present invention has in view are: to provide a simple and efficient prime mover, the motive power whereof may be readily and quickly renewed; to provide a prime mover having a simple and inexpensive construction; to provide a toy of the character mentioned, the parts whereof are easily and readily renewable; to provide a toy as characterized, the parts whereof may be separated for transportation and quickly and readily assembled; and to provide a toy of the character described with a simple and efficient rudder.

Drawings: Figure 1 is a side elevation of a boat constructed and arranged in accordance with the present invention; Fig. 2 is a bottom plan view of the same; Fig. 3 is a cross section taken on the line 3-3 of Fig. 2; Fig. 4 is a sectional view showing a modified form of construction of the boat body, the section being taken as on a line corresponding with the line 3-3 in Fig. 2.

In the preferred form of construction embodying the present invention, the hull 9 is formed from wood shaped as desired. Adjacent the stern of the hull 9 a fin-like rudder 10 is attached by means of a screw 11 or other similar fastening device which permits turning the rudder about said device, as on a pivot. The screw 11 is preferred, as it affords means for tightening or fixing the adjusted position of the rudder.

Adjacent the stern of the vessel, and preferably disposed between the end thereof and the rudder 10, is mounted a pendent bearing 46 arm 12. The arm 12 is formed from metal, and has a screw-threaded end for driving into the body of the hull 9, or if preferred, the end may be smooth to tightly fit a perforation or hole formed in said body. At 50 the lower end of the arm 12 is formed a relatively loose bearing for a propeller shaft 13.

The shaft 13 is of suitable length, and has a hook formed at one end thereof, the 55 other end being rigidly or fixedly mounted in the hub of a propeller 15 having blades

16. The shaft 13 and propeller 15 are installed in service position readily by passing the hook 14 and shaft 13 through the bearing in the end of the arm 12. It will be understood that they are as readily and easily dismantled by withdrawing them outward through said bearing.

In the present invention, the prime mover or motor is a twisted rubber band 17. To anchor one end of said band a hook 18 is mounted on the hull 9, adjacent the bow thereof. The hook 18 opens forwardly, while the hook 14 opens in the opposite direction, or rearwardly. The band 17 is secured to the hook 14, as best shown in Fig. 1 of the drawings. It will be understood that bands of various sizes and quality may be employed as the prime mover or motor.

In Fig. 4 of the drawings, a modified form of the invention is shown, the modification consisting in substituting for the hull 9 as formed of wood, a hull 19 formed of sheet metal. In this form, a deck 20 is provided, the deck being secured to the hull by the curled edges 21. The curled edges 21 may be replaced by a soldered or otherwise tacked joint, which, by paint or other material, may be filled against the admission of water.

In the modified form of the invention, the mimic smoke-stack 22 is secured to the upper surface of the deck 20, whereas, in the preferred form of the invention, the smoke-stack 23 is formed from wood, and secured in position in the solid hull 9 by being driven through holes provided therein, as best shown in Fig. 3 of the drawings.

Having a bow constructed as herein shown and described, the operation is as follows: If the toy has been separated for convenience in transportation, by having removed the band 17 and the propeller 15, these are now installed in place by inserting first the hook 14 and subsequently the shaft 13 through the bearing formed in the lower end of the arm 12. A band 17 is then adjusted by causing the ends of the same to engage the hooks 14 and 18. The band 17 may be shortened by forming one or more knots in the doubled band, as shown in Fig. 1 of the drawings. The rudder 10 is adjusted to guide the boat in its proposed flight. This may require that the screw 11 be loosened to relieve the tension on the base 24 forming the rest for the rudder 10. When the rudder is adjusted, as for instance

to follow a curved path, being set as shown in dotted lines in Fig. 2 of the drawings, the screw 11 is tightened to hold the rudder in the adjusted position. The proprietor 5 of the boat, by reversely revolving the propeller 15, twists the band 17 until a relatively strong torque is produced in said band. Holding the propeller against movement, the proprietor now places the boat in 10 water, setting it on its initial course. The propeller being now released, the band 17 untwists, revolving with greater or less rapidity the propeller 15, with the result that the boat is speeded on its course.

15 Claims:

1. A motor boat as characterized, comprising a floating hull; a pendent arm mounted adjacent the stern of said hull, to extend below the same forming a ballast 20 therefor, said arm having a bearing at the lower end thereof; a short shaft rotatively and removably mounted in said bearing; a propeller fixedly mounted on said shaft in the rear of said arm; an exposed twisted 25 band motor operatively connected with said shaft and with said hull, adjacent the bow thereof; and exposed means for holding the forward end of said motor.
2. A motor boat as characterized, comprising a floating hull; an exposed pendent arm mounted adjacent the stern of said hull, to extend below the same forming a ballast 30 therefor, said arm having a bearing at the lower end thereof; a short shaft rotatively and removably mounted in said bearing to bear against said arm; an exposed twisted-band motor operatively and removably connected with said shaft and with said hull, adjacent the bow thereof; and an exposed forwardly-opening hook 35 mounted on said hull to engage said motor.
3. A motor boat as characterized, comprising a floating hull; a fully exposed

pendent arm mounted adjacent the stern of said hull to extend below the same forming a ballast therefor, said arm having a bearing at the lower end thereof; a shaft rotatively and loosely mounted in said bearing to bear against the rear of said arm; an exposed twisted band motor operatively and removably connected with said shaft and with said hull, adjacent the bow thereof; an exposed forwardly-opening hook mounted on said hull to engage said motor; and a hook formed on said shaft for engaging said motor.

4. A motor boat as characterized, comprising a shallow floating hull; a fully exposed pendent arm mounted adjacent the stern of said hull to extend below the same forming a ballast therefor, said arm having a bearing at the lower end thereof; a shaft mounted in said bearing, having at the forward end thereof an exposed hook, the center of said hook being alined with the axis of said shaft; a propeller rigidly mounted on said shaft to bear against said arm; a forwardly-opening fully exposed hook mounted on said hull, adjacent the bow thereof; a twisted rubber-band motor operatively and removably engaging the hook on said shaft and the hook on said hull; a fin-like member mounted on the under side of said hull, forward of said arm; and fastening means for said member adapted for holding said member in adjusted position to counterbalance any lateral displacement of said hull by said propeller.

In testimony whereof I have signed my name to this specification in the presence of two subscribing witnesses.

HENRY BERGH.
